UNITED STATES PATENT OFFICE.

FARLEY JAMES WILKINSON, OF GARY, INDIANA.

DIESTOCK.

Application filed May 19, 1924. Serial No. 714,419.

My invention relates to improvements in die stocks, and it consists in the combinations, constructions, and arrangements, herein described and claimed.

5 An object of my invention is to provide a die stock of the type described which is a part of the mechanism shown in my copending application for patent on pipe cutter and threader, Serial No. 713,781, filed May 10, 1924. In my co-pending application I showed a die stock A, a pipe cutter B, and a housing C, which enclosed the die stock and cutter. The housing D for a motor, also comprised a portion of the housing C. 15 The housings C and D are supported by a carrier E. This in turn is slidably disposed on a guide frame F and adapted to be moved vertically with respect to the guide frame by means of a thumb screw G. 20 The principal object of the die stock or threader is to provide a threader which is adapted to receive a pipe and to be centered with respect to the pipe, and also to the cutter, the die stock being further provided 25 with means for moving the dies away from the pipes so as to permit the pipe to be withdrawn without the necessity of rotating the pipe with respect to the die stock.

A further object of my invention is to 30 provide a device of the type described which is compact in structure, and which therefore may be used with a hand lever instead of the motor driven apparatus as shown in the present drawings.

35 A further object of my invention is to provide a device of the type described which is adapted to be quickly adjusted with respect to different sized pipes, whereby a greater amount of work may be turned out 40 in a given length of time than is capable with the standard die stocks.

A further object of my invention is to 45 provide a device of the type described which has novel means for automatically taking up the wear without in any way interfering with the accuracy of the device.

50 Other objects and advantages will appear in the following specification, and the novel features of the invention will be particularly pointed out in the appended claims.

My invention is illustrated in the accompanying drawings, forming part of this application, in which—

Figure 1 is a side elevation of the device

as shown in combination with the cutter and 55 motor driving mechanism.

Figure 2 is a view partly in section and 60 partly in elevation showing the die carrier removed so as to permit the dies to be removed from the device,

Figure 3 is an end elevation of the device,

Figure 4 is a sectional view along the line 4—4 of Figure 3,

Figure 5 is a sectional view along the line 5—5 of Figure 3,

Figure 6 is a side elevation of a portion 65 of the device,

Figure 7 is a section along the line 7—7 of Figure 3,

Figure 8 is a plan view of another portion 70 of the device, and

Figure 9 is a section along the line 9—9 of Figure 5.

In carrying out my invention I provide a 75 housing C which encloses the die stock A and cutter B of the device. The housing C is supported by a housing D, the housing D in turn enclosing a motor, which is operatively connected to the die stock A, and to the cutter B. The housing D is carried by a carrier E, which is slidably mounted upon the frame F. The frame F in turn is pivotally carried by a support H. The vise, (not shown) is carried by the support 80 H, and is adapted to support the pipe to be cut, this pipe being received in the threader A and the cutter B. The housing D is adapted to be moved vertically by means 85 of a thumb screw G. In this manner, the threader A and cutter B may be aligned 90 with the pipe to be cut and threaded. The parts mentioned so far have been described in detail in my co-pending application, and therefore need no further description at this point.

95 The die stock or threader is clearly shown in Figures 3 and 4, and it will be noted from these figures that the die stock is enclosed in a casing ring 1 which has gear teeth 2 cut in its outer periphery. The teeth 2 are in mesh with a worm 3 that in turn is mounted upon a shaft 4. The shaft is operatively connected to a motor 5 by means 100 of a link belt 6. When the motor is operated, it will rotate the casing 1.

An outer sleeve 7 is mounted in the bore 8 of the casing ring 1 and has lugs 9 which are adapted to abut lugs 10 of the casing,

- whereby the sleeve 7 is rotated when the casing ring 1 is rotated. The lugs 9 are shorter in length than the length of the casing ring 1, so as to permit the sleeve 7
- 5 to move slightly with respect to the casing ring 1. Rollers 11 are carried by the sleeve 7 and permit the movement. The rollers 11 are disposed between certain of the lugs 9 and 10, (see Figure 3).
- 10 The sleeve 7 is provided with inwardly extending lugs 12 which are slidably received in slots 13 of a body portion 14. The lugs 12 turn the body portion 14 when the sleeve 7 is turned, and also guide the
- 15 body portion when the body portion is moved longitudinally with respect to the sleeve 7.
- In Figure 4 I have shown the body portion 14 as being provided with a bore 15 in
- 20 which a sleeve 16 is slidably disposed. The sleeve 16 is locked to the body portion 14 by means of pins 17, (see Figure 5). The pins are carried by the sleeve 16 and are slidably disposed in grooves 18 in the bore
- 25 15. The groove 18 is of a certain shape so as to lock the sleeve 16 in the position shown in Figure 5, and to also permit the body portion 14 to move outwardly into the
- 30 position shown in Figure 2. The sleeve 16 is rotated slightly with respect to the body portion 14 so as to dispose the pin 17 in the leg 19 of the groove, whereupon a spring
- 35 20 will move the body portion 14 into the position shown in Figure 2.
- 35 When the body portion 14 is in the position shown in Fig. 2, dies 21 that are slidably disposed in the bores 22 in the body portion are adapted to be removed if desired. It will be noted from Figures 2 and
- 40 3 that the dies have projections 23 that are slidably received in L-shaped grooves 24 in the sleeve 7. The grooves 24 are inclined, (see Figure 5) so as to move the dies 21 inwardly when the body portion 14 is moved
- 45 into the bore of the sleeve 7. In this manner, the dies may be adjusted for various sized pipes by merely moving the body portion 14 with respect to the sleeve 7.
- The means for moving the body portion
- 50 14 into the sleeve 7 is clearly shown in Figure 6, and comprises a ring 25 that is secured to the sleeve 16 by means of a disc 26 and a plate 27. The disc 26 has a recess 28 adjacent to its outer edge, which, with
- 55 the plate 27, forms a groove in which the ring 25 is adapted to rotate. The ring 25 is adapted to move with respect to the sleeve 16 and is operatively connected to the sleeve 7 by means of racks 29 and a ring 30. The
- 60 ring 30 is threaded on its interior surface, these threads meshing with the threads 31 on the racks 29. The ring 30 is locked to the sleeve 7 by means of a disc 32, (see Figure 5). It will be apparent from this con-

struction that when the racks 29 are moved 65 with respect to the ring 25, the body portion 14 will be moved with respect to the sleeve 7.

This movement is accomplished by means of a cam-shaped strip 33 that is carried 70 by the ring 25. In the present form of the device I have shown two cam-shaped strips 33, each one of these being connected to its respective rack 29. The racks 29 have grooves 34 therein which receive the strips 75 33 and it will therefore be apparent that when the ring 25 is rotated, the strips 33 will move the racks 29 with respect to the ring 25, and will therefore cause the body portion 14 to be quickly moved in either direction. After the ring 25 has been rotated, it may be locked to the racks 29 so as to prevent further movement of the body portion 14 with respect to the sleeve 7. This is accomplished by means of a locking pin 85 35, (see Figure 9). The pin 35 is carried by a casing 36, which in turn is supported by the ring 25. A spring 37 bears against the pin 35 and yieldingly holds the pin in a recess 38 in one of the racks 29. A handle 90 39 permits the pin 35 to be removed from the recess 38, whereby the ring 25 may again be rotated with respect to the racks 29. When the ring 25 is turned, it quickly moves the racks 29, and thus causes quick adjustment of the dies 21.

When it is desired to move the racks 29 more slowly, so as to permit the dies 21 to be finely adjusted, the ring 30 is actuated. As heretofore stated, the ring 30 is secured 100 to the sleeve 7 by means of the disc 32, whereby a rotation of the ring 30 will move the sleeve 7 with respect to the body portion 14. After the ring 30 has been moved, it may be locked against further movement by 105 means of the locking device shown in Figure 8. This device comprises a screw 40 which is disposed with in a bore 41 of the ring 30. An operating handle 42 is rigidly secured to the screw 40 and is locked 110 against rotation with respect to the ring 30 by means of a leaf spring 43, this spring being received within a recess 44 in the operating handle 42. A latch member 45 is pivotally secured to the ring 30 at 46 and has prongs 47 that are adapted to enter recesses 48 in the sleeve 7. When it is desired to remove the prongs 47 from the recesses 48, it is first necessary to remove the leaf spring 43 from the recess 44, whereupon the operating handle 42 may be rotated 115 so as to move it away from the latch member 45 and permit the latch member to be moved outwardly so as to free the prongs 47 from the recesses 48.

In Figure 7 I have shown a roller 49 which is carried by the body portion 14, and which bears against the sleeve 7 so as to permit

the body portion 14 to move with respect to the sleeve 7. It will be noted from Figure 3 that I have provided two of such rollers. The pins 11 and the rollers 49 5 permit the various parts to move with respect to each other so as to adapt the device to various kinds of work.

In Figures 5 and 9 I have shown a novel means for centering the device with respect 10 to the pipe. This means is carried by the sleeve 16 and is enclosed by a flange 50 of the sleeve 16 and by the disc 26. In Figure 5 it will be noted that the disc 26 and flange 50 enclose the plate 27 and a plate 51. The plate 15 51 has recesses 52 therein which receive projections 53 that are integral with the flange 50 and sleeve 16. Screws 54 connect the disc 26 to the sleeve 16, and are received in openings 55 in the projections 53. The 20 screws 54 pass through openings 56 in the plate 27 and not only prevent rotation of the plate 27 with respect to the disc 26, but also bind the plate to the projections 53. The plate 51 is adapted to be moved with 25 respect to the plate 27 and this is accomplished by means of a thumb screw 57 which is pivotally connected at 58 to the plate 27 and is operatively connected to the plate 51 at 59. When the thumb screw 57 is actuated, 30 it will draw the lug 60 to which it is attached toward the pivotal point 58, and will therefore rotate the plate 51 with respect to the plate 27. In Figure 9 I have shown the plate 27 as being provided with 35 arcuate-shaped slots 61, these slots receiving arcuate-shaped fingers 62. The fingers 62 have projections 63 that are slidably received in the slots 64 in the plate 51. It will therefore be seen from this construction that 40 when the plate 51 is moved with respect to the plate 27, the finger 62 will be moved toward or away from the longitudinal axis of the sleeve 16.

From the foregoing description of the 45 various parts of the device, the operation thereof may be readily understood. In Fig. 1 I have shown how the die stock is mounted with respect to the cutter, and with respect to the support H. In threading 50 a pipe, the pipe is first clamped in the vise, (not shown), and the die stock is then moved on over the pipe so as to dispose the pipe in the sleeve 16. The thumb screw 57 is now actuated so as to cause the fingers 55 62 to center the pipe with respect to the die stock. The ring 25 is now moved so as to cause the pin 35 to enter the recess 38, and lock the racks 29 to the ring. This movement draws the body portion 14 into the 60 sleeve 7 and also moves the dies 21 toward the pipe. The ring 30 is now actuated, whereby the dies may be set so as to cut the thread in the pipe. The ring 30 is locked against movement by means of the latch 45. 65 The motor 5 may be started, and will rotate

the casing 1 so as to move the dies 21 around the pipe, which is being cut. As shown in Figure 5, the dies have teeth cut on their inner surfaces, and these teeth bite into the pipe and cut the threads in the pipe while 70 the die stock is being rotated on the pipe.

After the thread has been cut, the pin 35 is removed from the recess 38, and the ring 25 is rotated so as to release the dies from the pipe. In this way, the pipe may be removed without the necessity of rotating the die stock with respect to the pipe. In Figure 5 I have shown two markers 63' and 75 64' which permit the device to be set for various sized pipes. The marker 64' is carried by the sleeve 7. Lines 65 on the marker 64' are placed in a predetermined position so as to enable the operator to know that when the mark 66 on the marker 63' is aligned with either one of these lines, the die stock is adjusted for a certain sized pipe. In Figure 3 I have shown the markers 80 as being positioned adjacent to the racks 29.

In assembling the sleeve 16 to the body portion 14, the sleeve is disposed so as to cause the pins 17 of the sleeve to be received in the legs 67 of the grooves 18. The sleeve is now moved inwardly into the body portion until the pins strike the branches 68 of the grooves. A slight rotation of the sleeve will now cause the pins to be received in the legs 19. The pins 17 are disposed in the position shown in Figure 5, when the device is adjusted so as to thread pipes. To prevent the movement of the sleeve 16 with respect to the body 14, I provide a locking screw 69 that is partly received in the body portion 14 and partly received in the sleeve 16, (see Figure 3). In this way, the sleeve 16 is prevented from rotation with respect to the body portion 14. 90

In changing the dies, the screw 69 is first removed from the sleeve 16, so as to permit the sleeve to be turned with respect to the body portion 14. The locking pin 35 is released from the recess 38, and the latch 45 is released from the recesses 48. The flange 50 and the sleeve 16 may now be turned so as to dispose the pins 17 in the legs 19 of the groove 18. The spring 20 will now force the body portion 14 outwardly with respect to the sleeve 7, so as to dispose the pins 17 in the ends α of the legs 19. The pins 17 prevent further movement of the body portion 14 with respect to the sleeve 16. When this movement takes place, the body portion 14 is disposed in the position shown in Figure 2. The dies 21 are free so that they may be removed and other dies substituted therefor if desired. 100

It will be apparent from the construction described that the device may be adjusted for various sized pipes, so as to thread these 105 pipes. Moreover the body portion 14 may 110

be moved into the position shown in Figure 2 so as to remove the dies if desired. One of the principal objects of the device lies in the fact that the dies are moved inwardly when the body portion 14 is moved with respect to the sleeve. In this way, the dies may be moved away from the pipe after the pipe has been threaded so that the pipe may be removed from the die stock without the necessity of rotating the die stock on the pipe.

The spring 20 not only provides a novel means for moving the body portion 14 with respect to the sleeve 7, but also provides an automatic means for taking up wear between these two parts. It will be noted from Figure 5 that the spring 20 bears against the body portion 14 and also against the sleeve 7. The body portion 14 and the sleeve 7 are connected to each other by means of the ring 25, the racks 29, and the ring 30. If any wear takes place between the plate 27 and the racks 29, as at the points Y and Z, (see Figure 4), this wear is automatically taken up by means of a spring 20. The ring 25 acts as a fulcrum between the plate 27, and the racks 29. In this way, there is always a positive connection between the body portion 14 and the sleeve 7. As shown in Figure 5 the body portion 14 is provided with projections 76 which are disposed directly above and below the dies 21 and act as additional guiding means for the dies. These projections enter the L-shaped slots 24 in the sleeve 7 when the body portion 14 has been moved into the bore 15 a predetermined distance. In this way, the projections aid in locking the body portion 14 to the sleeve 7 so as to cause these parts to rotate as a unit.

As heretofore stated, the fingers 62 are adapted to be moved into the interior of the sleeve 16. Openings 75 in the sleeve 16

are provided for this purpose and receive the fingers 62.

I claim:

1. A die stock comprising an outer sleeve, a die carrying body slidably disposed in said sleeve, an inner sleeve slidably mounted in said body, means for locking said inner sleeve to said body, dies carried by said body and being movable toward and away from each other when said body is moved in said outer sleeve and means for permitting said body to move with respect to said inner sleeve to move said dies. 55

2. A die stock comprising an outer sleeve, a die carrying body slidably disposed in said sleeve, an inner sleeve slidably mounted in said body, means for locking said inner sleeve to said body, dies carried by said body and being movable toward and away from each other, said dies being moved when said body is moved with respect to said outer sleeve, and means for quickly moving said dies, said means including spring means for moving said body with respect to said inner sleeve. 60 65

3. A die stock comprising an outer sleeve, a die-carrying body slidably disposed in said sleeve, an inner sleeve slidably mounted in said body, means for locking said inner sleeve to said body, dies carried by said body and being movable toward and away from each other, and a spring disposed between said die-carrying body and said outer sleeve and being adapted to move said die-carrying body into a position to free the dies from said outer sleeve, said locking means permitting a quick movement of said die-carrying body with respect to said outer sleeve and inner sleeve when said die-carrying body is rotated into a predetermined position. 70 75 80

FARLEY JAMES WILKINSON.
